UNITED STATES PATENT OFFICE.

WALTER G. CLARK, OF NEW YORK, N. Y.

ELECTRIC-LAMP SOCKET.

1,018,480.

Specification of Letters Patent. Patented Feb. 27, 1912.

Application filed June 27, 1910. Serial No. 569,147.

To all whom it may concern:

Be it known that I, WALTER G. CLARK, a citizen of the United States, and a resident of the borough of Manhattan, city, 5 county, and State of New York, have invented certain new and useful Improvements in Electric-Lamp Sockets, of which the following is a specification, accompanied by drawings.

- 10 This invention relates to electric lamp sockets for incandescent lamps, and the objects of the invention are to improve upon the construction and operation of such sockets and enable the current to be readily 15 switched on and off at the socket, even if the lamp is inconveniently located, in such position that the ordinary key or chain would be inaccessible or reached with difficulty.
- 20 Further objects of the invention will hereinafter appear and the invention consists of a lamp socket substantially as hereinafter described and claimed in this specification and shown in its preferred form in the accompanying drawings, in which—

Figure 1 is a side elevation partly broken away of a lamp socket embodying the invention; Fig. 2 is a longitudinal sectional view of Fig. 1; Fig. 3 is a top plan view of 30 the device shown in Fig. 1, but rotated on its longitudinal axis ninety degrees counter clockwise; Fig. 4 is a longitudinal sectional view, partly in elevation on the line 4—4 of Fig. 3, looking in the direction of the arrows; Fig. 5 is a top plan view of a modification of the device in a position corresponding to that shown in Fig. 3 and Fig. 6 is a longitudinal sectional view, partly in elevation on the line 6—6 of Fig. 5, looking 35 in the direction of the arrows.

Referring to the drawings, the insulating block for the socket comprises the base member A, and the cap member B provided with the cap C for the lamp bulb D. The members A and B are relatively movable, in this 45 instance being relatively revolvable about their longitudinal axis. As shown, the pivot bolt E which is preferably hollow and provided with slotted sides F passes through the members A and B. One member, as the cap member B, is loose on said pivot bolt E, while the base member A in this instance is 50 suitably secured to said bolt as by means of the nut G. Beneath the head H of the bolt 55 lying inside of the cap C may be placed the washer J. The slotted end K of the bolt as

shown is thrust through apertures at each side of the cross bar L at the inner end of the conducting strip O which carries the binding screw P in the base member A, and 60 the nut G is screwed down upon said strip O over the end K of the bolt, so that the base member A in this instance turns with the bolt.

The insulating members A and B are normally locked from rotation and means are provided controlled by the lamp bulb for automatically unlocking said members when a lamp is secured in the cap C. As shown, the cap member B is centrally recessed at 70 Q into which may be set a locking plate R in the form of an annular disk provided with transverse notches or depressions S set into the cap member B. The metallic disk R is preferably provided to form a bearing 75 plate although it could be omitted and locking recesses formed in the material of the cap member B. A locking pin T is shown within the end of the hollow bolt E and projecting slightly beyond the head H of 80 the bolt within the cap C. This locking pin is slidable longitudinally within the bolt E and is provided with the transverse lugs U projecting through the slots F in the sides of the bolt. These lugs U are normally 85 pressed into the recesses S in the locking disk R by the compression spring V which is shown in this instance coiled within the bolt E between the end of the pin T and the bar L of the strip O. It is obvious that the 90 spring V may be located in any suitable position, as for instance, around the bolt E. A washer W is preferably placed around the bolt E over the locking plate R outside of the ends of the lugs U, so that these lugs 95 may move longitudinally within the washer W.

One of the insulating block members may be provided with an annular bearing shoulder, while the other is provided with an 100 annular recess which co-operates with the shoulder to center the said members. In this instance the cap member B is provided with the shoulder X while the base member A is provided with the recess Y into which the shoulder X projects. The base member A is also centrally recessed at Z to accommodate the movement of the lugs U of the locking pin T.

The base and cap members A and B are 110 provided with co-operating switch contacts for opening and closing the circuit through

the socket. One member, as the cap member B, is in this instance provided with a series of sloping teeth *a*, located around the shoulder or projection X and in a plane 5 transverse to the longitudinal axis of said cap member. These teeth or corrugations are formed in the cap member and the longitudinal faces *b* of the teeth form back-stops for the contact tongue *c* secured to the 10 base member A, so that said contact tongue *c* may pass over the surfaces of the teeth *a* in one direction only. In this instance four teeth *a* are shown, but there may be as many as desired. Alternate teeth *a* are provided 15 with conducting surfaces in the form of metallic plates *d* suitably secured upon the teeth as by means of the screws *e* which secure the cap C to the cap member B. Preferably the shoulder or projection X is longitudinally recessed at *f* to receive projecting portions *g* of the plates *d* and aids in centering and maintaining the plates *d* in position. The contact tongue *c* forming 20 one switch member is in this instance secured to the face of the base member A as by means of the screw *h* which also secures the contact strip or bracket *j* to the member A. Said bracket *j* is provided with the binding screw *k*. 25

If desired, the teeth or corrugations may be formed upon the exterior surface of the cap member as shown in Figs. 5 and 6 instead of upon the face of said member. In the modification shown in Figs. 5 and 6 30 the teeth *o* are located around the shoulder X upon the cap member B' and the curvilinear faces *p* of the teeth lie in longitudinal planes. Alternate teeth are provided with the curved conducting plates *q* having 35 ears *r* through which pass the screws *e*. The contact tongue *t* is in this instance secured to the side of the base member A', as by means of the bent tab or projection *u* through which passes the bracket screw *h*. 40

The remainder of the construction of the modification shown in Figs. 5 and 6 is in this instance similar to that shown in the 45 remaining figures.

It will be seen that in both the constructions shown the recesses S and the locking plate R lie transversely between the conducting plates *d* on the teeth *a*, while the contact tongue *c* or *t* is so located upon the base member A that when the base and cap 50 members are locked together with the lugs U of the locking pin T in the recesses S, said tongue C lies upon one of the insulating teeth *a*, so that contact is broken through the block. Any suitable arrangement and 55 location of the parts may be devised which will bring about this operation. When the lamp bulb D is inserted in the cap C, the inner end *w* of the bulb will bear against the locking pin T and push said locking 60 pin inwardly carrying the lugs U out of the 65

recesses S, thereby unlocking the members A and B, so that one member may be turned relatively to the other to bring the contact tongue *c* upon one of the conducting plates *d*, thus closing the circuit through the 70 socket.

In assembling the parts, the pivot bolt E is first inserted through the cap member B with the locking plate R in position in said cap member around the bolt. The locking pin T is then inserted in the bolt with the lugs U in the slots F of the bolt. The washer W is placed over the bolt and the spring V is placed in the bolt. The base member A is then placed over the bolt and the slotted end K of the bolt inserted through the apertures at each side of the cross bar L in the strip O. The nut G is screwed on to the end of the bolt F and the spring V forces the lugs U into the locking 80 recesses S, so that the members A and B are locked together with the contact tongue *c* on one of the insulating teeth *a*. The cap member B and cap C are thus held from movement as the lamp bulb is inserted in 85 the cap C. After the locking pin T is released by the insertion of the bulb, the circuit is completed by continuing to turn the cap member B. The cap member B may be turned by grasping the lamp bulb and 90 by this means the socket may be readily manipulated, although the socket itself may be inaccessible, since the lamp bulb may readily be grasped. The locking lugs U of the locking pin T bear upon the high portion of the plate R until the contact tongue *c* leaves the contact plate *d* in which case the lugs U snap back into the recesses S. The back stops *b* on the teeth *a* prevent the 95 cap member from being turned backward, so that the circuit is made and broken by turning the cap member always in the same direction.

I claim and desire to obtain by Letters 100 Patent the following:

1. An electric lamp socket comprising relatively movable insulating base members provided with coöperating switch contacts and normally locked with the switch contacts open, and means for automatically unlocking said base members when the lamp bulb is inserted in the socket.

2. An electric lamp socket comprising relatively revoluble insulating base members provided with coöperating switch contacts and normally locked from rotation with the switch contacts open, and means for automatically unlocking said base members when the lamp bulb is inserted in the socket.

3. An electric lamp socket comprising relatively movable insulating base members provided with coöperating switch contacts and normally locked with the switch contacts open, one member having a cap for the reception of a lamp, and means controlled 130

by the lamp bulb for automatically unlocking said base members when a lamp is secured in the cap, to permit one member to be moved relatively to the other and make 5 contact at the switch contacts.

4. An electric lamp socket comprising relatively revoluble insulating base members provided with coöperating switch contacts and normally locked from rotation, with the 10 switch contacts open, one member having a cap for the reception of a lamp, and means controlled by the insertion of the lamp in the cap for unlocking the base members and permitting one member to be rotated relatively to the other to make contact at the 15 switch contacts.

5. An electric lamp socket comprising centrally pivoted relatively revoluble base members, one member having a peripheral 20 series of sloping teeth formed with back stops, alternate teeth having contact surfaces, and the other member having a contact tongue adapted to coöperate with said teeth, means for locking said members together, and means for automatically unlocking said base members when the lamp bulb is inserted in the socket.

6. An electric lamp socket comprising centrally pivoted relatively revoluble base 30 members, one member having a peripheral series of sloping teeth formed with back stops, alternate teeth having contact surfaces, and the other member having a contact tongue adapted to coöperate with said 35 teeth, a cap secured to one member, and a longitudinally movable spring pressed locking pin projecting into said cap and adapted to be moved longitudinally by the insertion of the lamp bulb in the cap to unlock 40 said base members.

7. An electric lamp socket comprising an insulating block divided transversely into a base member and a relatively revoluble cap member, one member having a circular 45 row of teeth provided with back stops, alternate teeth having conducting surfaces, the other member having a metallic tongue adapted to engage said teeth, a cap secured to said cap member, a longitudinal pivot 50 bolt passing loosely through one of said block members and secured to the other

member, and a longitudinally movable spring pressed locking pin normally projecting within the cap, and adapted to be moved longitudinally by the lamp bulb when secured in the cap. 55

8. An electric lamp socket comprising relatively revoluble insulating base and cap members provided with coöperating switch contacts, a cap secured to said cap member, 60 a longitudinal pivot bolt passing loosely through one member and secured to the other member, and a longitudinally movable spring pressed locking pin normally projecting within the cap and adapted to be 65 moved longitudinally of the lamp bulb when secured in the cap.

9. An electric lamp socket comprising relatively revoluble insulating base and cap members provided with coöperating switch 70 contacts, a cap secured to said cap member, a hollow slotted longitudinal pivot bolt passing loosely through one member and secured to the other member, and a spring pressed pin slidable longitudinally in said 75 hollow bolt and normally projecting within the cap, said pin having transverse lugs projecting through the slots in the pivot bolt, and normally engaging that base member which is loose on the pivot bolt, whereby insertion of the lamp in the cap presses the locking pin inwardly and unlocks the base and cap members. 80

10. An electric lamp socket comprising relatively movable insulating base members, 85 provided with coöperating switch contacts normally locked against movement and means for automatically unlocking said base members when the lamp bulb is inserted in the socket, thereby permitting the switch 90 contacts to be operated by the rotation of the lamp bulb when the bulb is rotated in one direction, and a stop for preventing rotation in the opposite direction.

In testimony whereof I have signed this 95 specification in the presence of two subscribing witnesses.
